DESIGN FOR A BELT

Edna C. Bennett, New York, N. Y.

Application August 17, 1938, Serial No. 79,393

Term of patent 3½ years

To all whom it may concern:

Be it known that I, Edna C. Bennett, a citizen of the United States of America, residing in New York city, in the Borough of Manhattan, county and State of New York, have invented a new, original, and ornamental Design for a Belt, of which the following is a specification, reference being had to the accompanying drawing, forming part thereof, wherein,

The figure is a front perspective view of a belt showing my new design.

The characteristic feature of my design resides in the specific combination of the appliqued leaves with the beaded grape bunches and stems on the front of the belt, as shown.

I claim:

The ornamental design for a belt, substantially as shown and described.

EDNA C. BENNETT.
